United States Patent Office.

EDWIN L. BUSHNELL, OF POUGHKEEPSIE, NEW YORK.

Letters Patent No. 79,948, dated July 14, 1868.

IMPROVEMENT IN HARVESTER-CUTTER SHARPENER.

The Schedule referred to in these Letters Patent and making part of the same.

TO ALL WHOM IT MAY CONCERN:

Be it known that I, EDWIN L. BUSHNELL, of Poughkeepsie, in the county of Dutchess, and State of New York, have invented a new and improved Harvester-Sharpener; and I do hereby declare that the following is a full, clear, and exact description thereof, which will enable those skilled in the art to make and use the same, reference being had to the accompanying drawings, forming part of this specification.

The object of this invention is to provide an instrument for sharpening the cutters of reaping and mowing-machines.

The ordinary rifle used for sharpening scythes cannot well be adapted to this purpose. It requires a different-shaped instrument to fit in between the knives or cutters of harvesters or mowers to operate with the desired effect.

And the invention consists in making the blade of the sharpener rhomboidal shaped, so that it will fit in between the cutters, and produce, with a drawing stroke or motion, the desired effect.

Figure 1 is a perspective view of the sharpener.

Figure 2 is a cross-section of the same, through the line *x x*.

Similar letters of reference indicate corresponding parts:

By forming the blade A in this manner, I get a sharpener with four sides of equal superficial measurement, and of equal value for the use intended.

The sharp corners or acute angles formed by the sides allow it to reach portions of the cutters that a square rifle sharpener could not reach, while the flat sharpening-surface renders it much more effective than any oval-shaped rifle can be for the particular purpose intended.

Having thus described my invention, I claim as new, and desire to secure by Letters Patent—

As a new and improved article of manufacture, the rhomboidal-shaped cutter-sharpener, substantially as described, and for the purposes set forth.

The above specification of my invention signed by me, this 27th day of February, 1868.

EDWIN L. BUSHNELL.
